UNITED STATES PATENT OFFICE.

STEPHEN M. WIRTS, OF DETROIT, MICHIGAN, ASSIGNOR, BY MESNE ASSIGNMENTS,
TO CHARLES P. MONASH, OF CHICAGO, ILLINOIS.

TABLE.

1,243,123.

Specification of Letters Patent. Patented Oct. 16, 1917.

Application filed September 29, 1913. Serial No. 792,262.

To all whom it may concern:

Be it known that I, STEPHEN M. WIRTS, a citizen of the United States of America, and resident of Detroit, Wayne county, Michigan, have invented a certain new and useful Improvement in Tables, of which the following is a specification.

My invention relates to tables of that kind in which the construction is such that 10 the structure can be knocked down and assembled flatwise together for transportation.

Generally stated, the object of my invention is to provide a novel and highly effective knock down table.

15 A special object is to provide a knock down table adapted more particularly for use in combination with folding beds.

It is also an object to provide a knock down table construction which will be strong 20 and serviceable, easy to put together and take apart, and which can be readily connected with the folding bed, whereby a table bed is provided which can be shipped at less cost than heretofore.

25 A further object is to provide certain details and features of construction tending to increase the general efficiency of a knock down table of this particular character.

To these and other useful ends my invention 30 consists in matters hereinafter set forth and claimed.

In the accompanying drawings:

Figure 1 is a front elevation of a knock down table embodying the principles of my 35 invention.

Fig. 2 is an end elevation of said table.

Fig. 3 is an enlarged section on line 3—3 in Fig. 2.

40 Fig. 4 is a detail section on line 4—4 in Fig. 3.

Fig. 5 is a perspective of one end section of said table.

Fig. 6 is a perspective of one end portion of the rear side wall.

45 Fig. 7 is a perspective of one end portion of the foot board of said table.

As thus illustrated, my invention comprises a pair of end sections A, (see Fig. 5) one for each end of the table. Each end section 50 comprises a pair of legs a connected together by a cross bar a^1 , and by an end wall a^2 . The bar a^3 extends from one leg to the other, inside of the walls a^2 , and at the lower edge thereof, in order to form a support 55 for the bed frame (not shown), the struc-

ture being what is known as a table bed. The front legs a are recessed at the top, forming reduced portions a^4 into which are mortised the ends of the wall a^2 , and which are provided on the opposite sides with 60 grooves a^5 . The shoulder a^6 of these legs are provided with sockets a^7 . At the other side of the table the legs are provided with recesses a^8 forming shoulders a^9 for the bar a^3 . These legs are also provided with 65 vertical slots a^{10} provided with upper and lower pins a^{11} , and with a hole a^{12} .

As shown in Fig. 6, the rear side section or wall B is provided at its ends with hooks b that enter the slots a^{10} and engage the 70 pins a^{11} , whereby the end sections A are held in place. A screw b^1 is inserted through the hole a^{12} , and through the hole b^2 in the upper hook b , at each end of the wall B, to hold said wall in position. By 75 removing these screws, the wall B can be lifted out of engagement with the end sections.

The top C is hinged at c to the upper edge of the wall B, and at c' to the upper edge 80 of the front section D. This wall D is provided at its lower edge with projections d that enter the sockets a^7 , and with ribs d^1 that enter the slots a^5 , whereby the wall D binds the end sections in place, and prevents the table from drawing apart. 85

Preferably, the foot board E engages the slots e in the bars a^1 , and is removably held in place by screws e^1 . This board E is of such size and location that the table has 90 the requisite clearance underneath. In other words, it may be used in the ordinary way as a library or desk table.

When knocked down or separated, the various sections of the table are adapted to 95 be placed flatwise together. Thus the cost of transportation is greatly reduced. The parts are also easily assembled together, and form a strong and firm structure. The table is therefore especially adapted for table 100 beds. But for the broader purposes of my invention, I do not limit myself to this particular use of the table.

In each end section, the space immediately above the strip or bar a^3 and immediately inside of the wall a^2 , forms a recess on the inside of the upper portion of the end section, which recess is closed at its rear end by that portion of the leg which contains the slot a^{10} , this recess being in line 110

2
with the front and rear legs. The said recess, it will be seen, when the end section is standing alone, is open at its top, closed at its bottom and lower edge, and open at its 5 front end. The sockets a^7 are in line with these recesses in the upper portions of the end sections, but are out of line vertically with the slots or grooves a^5 which receive the ribs d^4 on the inner surface of the front 10 section D, in the manner shown and described. Necessarily, therefore, the rear side section B is disposed between the rear legs, and in line therewith, being considerably shorter than the front side section D, 15 which latter has its end portions arranged to overlap the reduced upper portions of the front legs.

I do not limit myself to the exact construction shown and described.

20 What I claim as my invention is:

1. A knock down table comprising legs connected in pairs, forming end sections for the table, provided with engaging portions, a side section provided with means for removably engaging said portions, another side section, projections on the lower edge thereof to engage two of said legs, and a top section, one side section being shorter than the other side section, together with 25 hinges between said top and side sections.

2. A knock down table comprising legs connected in pairs, forming end sections for the table, provided with engaging portions, a side section provided with means for removably engaging said portions, another side section, and a top section, said last 35 mentioned side section having projections on the lower edge thereof, and two of said legs having sockets for said projections.

40 3. A knock down table comprising legs connected in pairs, forming end sections for the table, provided with engaging portions, a side section provided with means for removably engaging said portions, another 45 side section, one side section being shorter than the other side section, and a hinged top section, said last mentioned side section having means on the lower edge thereof for engaging two of said legs to hold the end 50 sections against displacement away from each other.

4. A knock down table comprising legs connected in pairs, forming end sections for the table, provided with engaging portions, 55 a side section provided with means for removably engaging said portions and holding said end sections in operative position,

another side section, one side section being shorter than the other side section, and a top section, the different sections thus separably combined forming a knock down table with a rectangular upper portion, the top and one side of which are displaceable to afford access to the interior thereof.

5. A knock down table comprising legs 65 connected in pairs, forming end sections for the table, provided with engaging portions, a side section provided with means for removably engaging said portions, another side section, and a top section, said last 70 mentioned side section having projections on the lower edge thereof, and two of said legs having sockets for said projections, said first mentioned side section being removably disposed between the two end sections, and 75 the other side section having its ends extended to overlap the front edges of said end sections.

6. A knock down table comprising legs connected in pairs, forming end sections for 80 the table, provided with engaging portions, a side section provided with means for removably engaging said portions, another side section, and a top section, said last mentioned side section having projections on 85 the lower edge thereof, and two of said legs having sockets for said projections, said end sections being formed with recesses extending along the inner sides thereof, each recess being closed at its lower edge, open 90 at its upper edge, closed at its rear end, closed at its outer side, and open at its front end, when the end sections are standing alone.

7. A knock down table comprising legs 95 connected in pairs, forming end sections for the table, provided with engaging portions, a side section provided with means for removably engaging said portions, another side section, and a top section, said last 100 mentioned side section having projections on the lower edge thereof, and two of said legs having sockets for said projections, said last mentioned side section having inner ribs, and said end sections having 105 grooves to engage said ribs, said grooves and sockets being out of line vertically.

Signed by me at Detroit, Michigan, this nineteenth day of September, 1913.

STEPHEN M. WIRTS.
